UNITED STATES PATENT OFFICE.

MARTIN CHRISTENSEN, OF RACINE, WISCONSIN, ASSIGNOR TO CHRISTENSEN MACHINE CO., OF RACINE, WISCONSIN, A CORPORATION OF WISCONSIN.

SIGNATURE-CONVEYER SUPPORT.

1,418,865.

Specification of Letters Patent. Patented June 6, 1922.

Application filed March 2, 1920. Serial No. 362,872.

To all whom it may concern:

Be it known that I, MARTIN CHRISTENSEN, a citizen of the United States, and resident of Racine, in the county of Racine and State of Wisconsin, have invented new and useful Improvements in Signature-Conveyer Supports, of which the following is a description, reference being had to the accompanying drawings, which are a part 10 of this specification.

The present invention relates to certain new and useful improvements in signature handling machines and refers more particularly to the means for supporting the 15 conveyer.

In signature machines, the signatures are straddled over the saddle conveyer and are thus presented to the stitcher-feeding mechanism, and considerable trouble has 20 been caused with former devices in that the leaves sway back and forth and oftentimes become folded under each other and are thus presented to the stitcher-feeding mechanism disarranged, in that the leaves of each 25 group are not in alignment.

Hence with the above inherent objections in mind, my invention has for its primary object to provide means for preventing this disalignment of the signatures and to 30 straighten out any folds which may be formed in the signatures due to such swaying movement.

A more specific object of this invention is to provide a novel form of signature 35 conveyer guide support so constructed as to perform the double function of supporting the conveyer guide and providing means for preventing the disalignment of the signatures.

With the above and other objects in view which will appear as the description proceeds, my invention resides in the novel construction, combination and arrangement of parts substantially as hereinafter described 40 and more particularly defined by the appended claims, it being understood that such changes in the precise embodiment of the hereindisclosed invention may be made as come within the scope of the claims.

In the accompanying drawing I have illustrated one complete example of the physical embodiment of my invention constructed according to the best mode I have

so far devised for the practical application of the principles thereof, and in which: 55

Figure 1 is a perspective view of a portion of a signature conveyer, a conveyer guide and guide supports embodying my invention.

Figure 2 is a perspective view of the 60 lower portion or vertical supporting standard for my improved support, and

Figure 3 is a perspective view, parts being broken away and in section, of the upper portion or inclined arm of my improved 65 support.

Referring now more particularly to the accompanying drawing, the numeral 5 designates a guide member which may be of any desired construction but in the present instance is channeled and has disposed therein the sprocket chain (not shown) of an endless saddle signature conveyer 6, the guide 5 being supported by one or more supporting standards 7, to be later described. 8 designates a tubular guard through which the lower portion of the conveyer 6 travels, and 9 designates a brace rod secured to each supporting standard and connecting the same with the signature machine proper (not shown). 75 80

My improved support consists of two parts, a lower vertical standard 10 and an upper arm 11 having its lower end 12 secured to a securing portion 13 formed on top of the vertical standard 10 and its other end channeled as at 14 for receiving the signature guide 5. The vertical standard 10 is formed with two supporting legs 15 having means for attachment to a suitable base 90 such as a flooring, and is provided with an intermediate transverse brace 16 providing a support upon which rests the conveyer guard 8. The transverse brace 16 has a centrally bored enlargement 17 formed on its under side intermediate of the supporting legs 15 for receiving the brace rod 9. 95

The upper portion or arm 11 of the supporting standard is inclined upwardly and oppositely to the normal direction of movement of the upper half of the conveyer 6 as depicted by arrow 18, see Figure 1. The arm 11 being inclined in a direction opposed to the direction of movement of the signature conveyer 6, and consequently of 100 105 signatures 19 being conveyed thereon, serves

as a straightening cam for the levers of the signatures to prevent them from being folded upon themselves and consequently thrown out of proper alignment, as will be 5 obvious.

The inclination of the arm 11 is such that its extreme upper end first engages the signatures 19 juxtapose their folds 20 and as they advance in the direction of the arrow 10 18, the arm 11 gradually straightens out any folds or irregularities therein, by reason of its inclination upwardly against the normal direction of movement of the conveyer 6 and signatures 19 mounted thereon.

15 From the foregoing description taken in connection with the accompanying drawing it will be at once apparent to those skilled in the art to which an invention of this character appertains that I have provided an 20 improved conveyer guide support which serves as means for preventing the dis-alignment of the signatures mounted on the conveyer, and which improved support is capable of production at a cost no greater 25 than the supports now in general use.

What I claim as my invention is:

1. In a signature conveyer, a conveyer support inclined in a direction opposite to the direction of movement of the conveyer, 30 and positioned to engage the signature leaves carried by said conveyer.

2. In a signature conveyer, a conveyer guide, a conveyer movable along the guide, and means adjacent the conveyer guide for engaging signature leaves carried by the 35 conveyer to prevent their becoming turned under.

3. In a signature conveyer, a conveyer guide, a conveyer movable along the guide, and a support for the conveyer guide including an arm secured to the guide and inclined downwardly therefrom in the direction of the normal movement of the conveyer, whereby the leaves of signatures being conveyed by the conveyer will be prevented 45 from becoming folded under, the inclination of the arm functioning as a leaf straightening cam.

4. In a signature conveyer, a conveyer guide, a conveyer movable along the guide, 50 and a support for the conveyer guide including a lower portion adapted for securing to a supporting base and an upwardly extending arm inclined in a direction opposite to the normal direction of movement of 55 the conveyer and having means on its extreme upper end for securement to the conveyer guide.

In testimony whereof, I affix my signature.

MARTIN CHRISTENSEN.
